(57) **CLAIM**

The ornamental design for a bicycle handlebar, as shown and described.

DESCRIPTION

FIG. 1 is a perspective view of a first embodiment of a bicycle handlebar showing my new design invention;

FIG. 2 is a front elevation view thereof;

FIG. 3 is a top plan view thereof;

FIG. 4 is a side elevation view thereof, the opposite side elevation view being a mirror image thereof;

FIG. 5 is a bottom plan view thereof;

FIG. 6 is a rear elevation view thereof;

FIG. 7 is a perspective view of a second embodiment of a bicycle handlebar showing my new design invention;

FIG. 8 is a front elevation view thereof;

FIG. 9 is a top plan view thereof;

FIG. 10 is a side elevation view thereof, the opposite side elevation view being a mirror image thereof;

FIG. 11 is a bottom plan view thereof; and,

FIG. 12 is a rear elevation view thereof.

The parts shown in dotted lines form no part of the invention.
